UNITED STATES PATENT OFFICE.

EDGAR E. SHELLEY, OF NEWARK, NEW JERSEY, ASSIGNOR TO THE ECONOMY PAPER COMPANY, OF NEWARK, NEW JERSEY, A CORPORATION OF NEW JERSEY.

PAPER-TOWEL-VENDING MACHINE.

Application filed July 18, 1922. Serial No. 575,863.

To all whom it may concern:

Be it known that I, EDGAR E. SHELLEY, a citizen of the United States, and residing at Newark, in the county of Essex and State of New Jersey, have invented certain new and useful Improvements in Paper-Towel-Vending Machines, of which the following is a specification, such as will enable those skilled in the art to which it appertains to make and use the same.

This invention relates to machines for vending paper towels, napkins and the like, and particularly to machines of this class in which the towels or napkins are manually removed or vended from the machine by grasping a projecting portion of the paper from which the towels or napkins are formed and pulling on said paper to actuate the mechanisms of the machine; and the object 20 of the invention is to provide a machine of the class and for the purpose specified comprising a simple, positive and accurately operating mechanism for vending paper towels, napkins or the like; a further object 25 being to provide an improved paper cutter or tearing device for severing the separate towels or napkins from a roll of paper, said cutter or tearing device cooperating with a paper feed drum, or an elongated aperture 30 therein with means within the drum for controlling and regulating the operation thereof and with other means on the drum cooperating with said cutter device for controlling the operation thereof; and with 35 these and other objects in view the invention consists in a machine of the class and for the purpose specified which is simple in construction, efficient in use and which is constructed and operated as hereinafter described and claimed.

The invention is fully disclosed in the following specification, of which the accompanying drawings form a part, in which the separate parts of my improvement are designated by suitable reference characters in each of the views, and in which:

Fig. 1 is a front view of my improved machine;

Fig. 2 a longitudinal sectional view 45 through the machine with parts of the construction broken away and in section;

Fig. 3 a transverse sectional view through

the machine, the section being partially on the line 3—3 of Fig. 2;

Fig. 4 a partial transverse section on the line 4—4 of Fig. 2 with the parts in a different position;

Fig. 5 a view similar to Fig. 4 but showing the parts in a different position; and,

Fig. 6 a view similar to Fig. 5 but showing the parts in a different position.

My improved machine is what I call a free vending paper towel or napkin machine and, in practice, I provide a suitable box-shaped casing 10 which is closed at the sides, back, top and bottom, and the front of which is closed by a door 11 adapted to swing upon a transverse rod 12 and held in a closed position by a rod 13 passed through a beaded portion 14 at the top of the cover and through the sides of the casing 10, said rod being provided with a head 15 at one end and with a cotter pin 16 passed through the other end thereof. The bottom of the casing 10 is bent upwardly as shown at 17 in Fig. 3 of the drawing to form a discharge aperture 18 through which the paper 19 from a roll 20 is adapted to pass.

The roll of paper 20 is mounted on a heavy shaft or rod 21 which enters angularly arranged guide channels 22 on the inner faces of the side walls of the casing, as clearly shown in Figs. 2 and 3 of the drawing, and the roll 20 of paper is adapted to rest upon the top of a feed drum 23, the periphery of which is provided with a rough facing 24, such as emery cloth or the like.

The drum 23 is hollow and provided at its ends with cap members 25 and 26 of open-work or web-like structure and having central bearings through which a shaft 27 is passed and on which said drum is free to rotate. The shaft 27 is mounted in a frame 10^a comprising V-shaped side members connected by three rods 10^b, and this frame fits within the casing 10 and is detachably mounted therein and is keyed in position by recesses 10^c engaging projections 10^d on the inner faces of the sides of the casing 10. The drum 23 is provided with an elongated aperture 28 at a predetermined point on the periphery thereof, the walls of said aperture being reinforced by metal facing sheets

29, and the cap member 25 is provided with a plurality of projecting annular flange members 30 cut away at intervals and provided where cut away with projecting pins 31. A shaft 32 is mounted longitudinally of and in front of the drum 23 and is rotatable in the sides of the frame 10^a, said shaft being provided with a cutter blade 33 having projecting teeth 34 and a central apertured portion 35, as shown in Fig. 2 of the drawing, and secured to the shaft 32 at one end thereof is a Geneva member 36 having four substantially arc-shaped or concave surfaces 37 adapted to operate in connection with the arc-shaped flanges 30 on the member 25 of the drum, and in the corner portions of the Geneva member are three elongated apertures 38 in connection with which the pins 31 are adapted to operate for intermittently operating said Geneva member and the cutter blade 33.

Pivotedly mounted in connection with the inner faces of the side walls of the casing 10 are two lever arms 39, the free ends of which carry a transverse roller 40 preferably composed of rubber, and this roller is adapted to bear on the periphery of the drum 23 in juxtaposition to the shaft 32, and a spring 41 is mounted on the shaft 32 centrally thereof and cooperates with the roller 40 to tensionally hold said roller in engagement with the drum.

Secured to the shaft 27 within the drum 23 and in juxtaposition to the cap member 26 thereof is a cam 42 and pivotally mounted in connection with the member 26 is a lever 43, which carries a roller 44 which operates in connection with the cam 42, and a spiral spring 45 is connected with the shaft of the roller 44 and with the drum as shown at 46 and serves to normally hold the roller in engagement with the periphery of the cam 42 at all times. Another lever 47 is pivoted to the member 26 as shown at 48 and is provided with a spring 49 for normally holding the same in engagement with the free end of the lever 43, and said lever 47 is provided with a projection 50 adapted to engage a pin 51 for intermittently tripping said lever or moving the same out of engagement with the lever 43 as hereinafter set out.

In the use of my improved machine, it will be apparent that the frame 10^a with the drum and the parts of the drum as well as the shaft 32 and its parts is set in the casing or in the lower portion thereof, after which the roller 40 is placed in position and a roll of paper 20 mounted in the casing with the free end thereof fed between the roller 40 and drum 23 and between the shaft 32 and said drum to the position shown in Fig. 3 of the drawing, or projecting slightly through the aperture 18 after which the door 11 is closed in the manner

hereinbefore set out. The machine is now ready for use and by pulling downwardly on the protruding portion of the paper 19, the drum 23 will be rotated in the first step of this operation, as indicated in Fig. 4 of 70 the drawing, in which it will be noted that the shaft 32 has been turned one quarter revolution by the engagement of one of the apertures 38 of the Geneva member 36 with one of the pins 31, and it will also be noted that the roller 44 on the lever 43 has been raised on the cam 42 against the tension of the spring 45 and the lever 47 has dropped beneath the lever 43 to take up the tension of the spring 45 and to permit of the free rotation of the drum by the paper. It being understood that the paper is under slight tension in the first named operation, or in the first step of the operation of rotating the drum, the next two steps is shown 80 in Fig. 5 of the drawing in which the Geneva member has been turned two-quarter revolutions by engaging two other pins 31 on said drum and the drum has been moved into position to bring the aperture 28 thereof in position to permit of the passage of the cutter blade 33 into the drum through said aperture, which operation cuts or tears the paper 19 over said aperture and dissects the same from the remainder of the paper, except where the aperture 35 is located in the cutter blade.

In Fig. 6 of the drawing, I have shown the beginning of the last movement of the drum 23 and Geneva member 36 in which 100 the plain corner, or unapertured corner of the Geneva member passes into one of the cut away portions of the flange 30, which is shown at 52 in Fig. 3 of the drawing and permits of the movement of the Geneva 105 member back into the position shown in Fig. 3 of the drawing, and this last named operation also extends the cut edge of the paper into the position shown in Fig. 3, it being understood that the cam 42 and roller 44 operate to produce this result. In the beginning of the last named operation as shown in Figs. 5 and 6 of the drawing, the lever 47 is moved out of engagement with the lever 43 to permit of the quick descent 110 of said lever on the cam, or the face of the cam 42 to impart a sudden rotary movement to the drum, while the cutter blade 33 passes into and out of the aperture 28 of the drum. It will also be apparent that one wall of 115 the aperture of the drum aids in moving the cutter blade out of the aperture 28 and in turning the Geneva member.

The above description completes one cycle 120 of the operation of the machine, and it will be understood that every time the projecting portion of the paper 19 is pulled through the machine, a predetermined portion thereof will be cut off for use, and the recess 53 125 in the face of the cam 42 will operate to 130

retain the roller 44 therein to hold the drum against movement, after the completion of one cycle of operation, it being understood that a decided pull is required on the paper 5 in order to raise the roller over the cam face from the position shown in Fig. 3 to that shown in Fig. 4.

By providing a transparent panel 54 centrally of the cover member 11 the condition 10 of the machine may be seen at all times and the time for replacing a new roll of paper determined without opening the door 11. It will also be apparent that by providing the frame 10^a as a unit for supporting the 15 drum 23 and the several parts mounted in connection therewith, as well as the shaft 32 and its parts, the operative mechanism of the machine may quickly and easily be placed in position in the casing 10 or removed therefrom for repair or other purposes, and while I have shown certain details of construction for carrying my invention into effect, it will be understood that I am not necessarily limited to these details, 20 and various changes therein and modifications thereof may be made, within the scope of the appended claims, without departing from the spirit of my invention or sacrificing its advantages.

Having fully described my invention what I claim as new and desire to secure by Letters Patent, is:—

1. A machine of the class described comprising a suitable casing, a drum rotatably mounted therein and provided with a longitudinal aperture in the periphery thereof, means for supporting a roll of paper in said casing in such manner as to rest upon the periphery of said drum, said paper being adapted to be passed over the drum and stretched across the aperture thereof at a definite point in the revolution of the drum, and normally extended through said casing, a cutter device mounted in juxtaposition to and longitudinally of the drum, and means for intermittently rotating said cutter device and for cutting that portion of the paper which is stretched over the aperture of said drum by rapidly passing the cutter blade through said aperture.

2. A machine of the class described comprising a suitable casing, a drum rotatably mounted therein and provided with a longitudinal aperture in the periphery thereof, means for supporting a roll of paper in said casing in such manner as to rest upon the periphery of said drum, said paper being adapted to be passed over the drum and stretched across the aperture thereof at a definite point in the revolution of the drum, and normally extended through said casing, a cutter device mounted in juxtaposition to and longitudinally of the drum, means for intermittently rotating said cutter device and for cutting that portion of the paper

which is stretched over the aperture of said drum by rapidly passing the cutter blade through said aperture, said drum being rotated by a pull on said paper, and means cooperating with the drum for imparting sudden rotary movement thereto in the operation of cutting said paper.

3. A machine of the class described comprising a suitable casing, a drum rotatably mounted therein and provided with a longitudinal aperture in the periphery thereof, means for supporting a roll of paper in said casing in such manner as to rest upon the periphery of said drum, said paper being adapted to be passed over the drum and stretched across the aperture thereof at a definite point in the revolution of the drum, and normally extended through said casing, a cutter device mounted in juxtaposition to and longitudinally of the drum, means for intermittently rotating said cutter device and for cutting that portion of the paper which is stretched over the aperture of said drum by rapidly passing the cutter blade through said aperture, said drum being rotated by a pull on said paper, means cooperating with the drum for imparting sudden rotary movement thereto in the operation of cutting said paper; and a roller mounted longitudinally of and cooperating with said drum in juxtaposition to said cutter device for holding the paper in firm engagement with the drum.

4. A machine of the class described comprising a suitable casing, a drum rotatably mounted therein and provided with a longitudinal aperture in the periphery thereof, means for supporting a roll of paper in said casing in such manner as to rest upon the periphery of said drum, said paper being adapted to be passed over the drum and normally extended through said casing, a cutter device mounted in juxtaposition to and longitudinally of the drum, means for intermittently rotating said cutter device and for passing the cutter blade thereof through the aperture of said drum to cut that portion of the paper passed thereover, said drum being rotated by a pull on said paper, means cooperating with the drum for imparting sudden rotary movement thereto in the operation of cutting said paper; a roller mounted longitudinally of and cooperating with said drum in juxtaposition to said cutter device, said drum and the parts cooperating therewith and said cutter device being mounted in a frame detachably mounted in the casing.

5. The herein described means for cutting paper and like material comprising a rotatable drum and a rotatable cutter device mounted longitudinally of the drum and adapted to cooperate therewith for cutting paper or the like passed over said drum between the same and said cutter device,

said cutter device involving a Geneva member cooperating with said drum and adapted to be intermittently rotated thereby.

16. A machine of the class described comprising a suitable casing, a drum rotatably mounted in the casing, a cutter blade mounted in juxtaposition to and longitudinally of the periphery of said drum and adapted to cooperate with an aperture therein, said cutter blade being placed in operative connection with said drum through a Geneva member whereby in the rotation of said drum, said cutter blade will be intermittently rotated.

17. A machine of the class described comprising a suitable casing, a drum rotatably mounted in the casing, a cutter blade mounted in juxtaposition to and longitudinally of the periphery of said drum and adapted to cooperate with an aperture therein, said cutter blade being placed in operative connection with said drum through a Geneva member whereby in the rotation of said drum, said cutter blade will be intermittently rotated, and means involving a cam and spring actuated lever mounted within and to said drum, for imparting sudden rotary movement thereto in a predetermined course of one complete revolution.

18. A machine of the class described comprising a suitable casing, a drum rotatably mounted in said casing, means for supporting a roll of paper in said casing and to permit of the automatic dropping of said paper onto the periphery of said drum, a cutter blade rotatably mounted in the casing in juxtaposition to and longitudinally of said drum, one side of said cutter blade being provided with a Geneva member and the corresponding side of said drum being provided with tracks and pin members in connection with which said Geneva member operates and by means of which said cutter blade are intermittently rotated in the rotation of said drum, and said drum being provided with a longitudinal aperture in connection with which the cutter blade operates to shear the paper passed between said drum and cutter blade at each revolution of said drum.

19. A machine of the class described comprising a suitable casing, a drum rotatably mounted in said casing, means for supporting a roll of paper in said casing and to permit of the automatic dropping of said paper onto the periphery of said drum, a cutter blade rotatably mounted in the casing in juxtaposition to and longitudinally of said drum, one side of said cutter blade being provided with a Geneva member and the corresponding side of said drum being provided with tracks and pin members in connection with which said Geneva member operates and by means of which said Geneva

member and cutter blade are intermittently rotated in the rotation of said drum, said drum being provided with a longitudinal aperture in connection with which the cutter blade operates to shear the paper passed between said drum and cutter blade at each revolution of said drum, a stationary cam mounted within said drum, and a member pivoted to said drum and normally held in engagement with said cam through tensional means whereby a sudden movement is imparted to said drum when said cutter blade extends into and out of the aperture of said drum.

20. A machine of the class described comprising a suitable casing, a drum rotatably mounted in said casing, means for supporting a roll of paper in said casing and to permit of the automatic dropping of said paper onto the periphery of said drum, a cutter blade rotatably mounted in the casing in juxtaposition to and longitudinally of said drum, one side of said cutter blade being provided with a Geneva member and the corresponding side of said drum being provided with tracks and pin members in connection with which said Geneva member operates and by means of which said Geneva member and cutter blade are intermittently rotated in the rotation of said drum, said drum being provided with a longitudinal aperture in connection with which the cutter blade operates to shear the paper passed between said drum and cutter blade at each revolution of said drum, a stationary cam mounted within said drum, a member pivoted to said drum and normally held in engagement with said cam through tensional means whereby a sudden movement is imparted to said drum when said cutter blade extends into and out of the aperture of said drum, and means pivoted to said drum and cooperating with said member for controlling the operation thereof.

21. A machine of the class described comprising a suitable casing, a drum rotatably mounted in said casing, means for supporting a roll of paper in said casing and to permit of the automatic dropping of said paper onto the periphery of said drum, a cutter blade rotatably mounted in the casing in juxtaposition to and longitudinally of said drum, one side of said cutter blade being provided with a Geneva member and the corresponding side of said drum being provided with tracks and pin members in connection with which said Geneva member operates and by means of which said Geneva member and cutter blade are intermittently rotated in the rotation of said drum, said drum being provided with a longitudinal aperture in connection with which the cutter blade operates to shear the paper passed between said drum and cutter blade at each revolution of said drum, a stationary cam

mounted within said drum, a member pivoted to said drum and normally held in engagement with said cam through tensional means whereby a sudden movement is imparted to said drum when said cutter blade extends into and out of the aperture of said drum, means pivoted to said drum and co-operating with said member for controlling

the operation thereof, and means for checking the rotation of said drum at each revolution. **10**

In testimony that I claim the foregoing as my invention I have signed my name this 14th day of July 1922.

EDGAR E. SHELLEY.
